[57] CLAIM

The ornamental design for a skate shoe, as shown and described.

DESCRIPTION

FIG. 1 is a right front perspective view of a skate shoe showing my new design, the broken line showing of a roller skate truck being illustrative of the environment only, and forming no part of the claimed design;
FIG. 2 is a right side elevational view thereof;
FIG. 3 is a front elevational view thereof;
FIG. 4 is a rear elevational view thereof;
FIG. 5 is a bottom plan view thereof;
FIG. 6 is a top plan view thereof; and
FIG. 7 is a left side elevational view thereof.
